Primary Examiner — Jeffrey D Asch*Assistant Examiner* — S. Bryan Reinholdt, Jr.*(74) Attorney, Agent, or Firm* — Neal, Gerber & Eisenberg, LLP(57) **CLAIM**

The ornamental design for a food cutting apparatus, as shown and described.

DESCRIPTION

FIG. 1 is a perspective view of the food cutting apparatus of the present invention;

FIG. 2 is a top plan view thereof;

FIG. 3 is a bottom plan view thereof;

FIG. 4 is a first side elevational view thereof;

FIG. 5 is a second side elevational view thereof, opposite from the first side elevational view;

FIG. 6 is a front elevational view thereof; and,

FIG. 7 is a rear elevational view thereof.

The broken lines in the drawings illustrate portions of the food cutting apparatus that form no part of the claim. The interior surfaces, within the almond-shaped openings at the top, form no part of the claimed design.
